UNITED STATES PATENT OFFICE.

WILLIAM STREETER RICHARDSON, OF BOSTON, MASSACHUSETTS, ASSIGNOR
TO THE BALL AND SOCKET FASTENER COMPANY, OF SAME PLACE.

FASTENING FOR GLOVES OR OTHER ARTICLES.

SPECIFICATION forming part of Letters Patent No. 557,703, dated April 7, 1896.

Application filed December 9, 1889. Serial No. 333,091. (No model.)

To all whom it may concern:

Be it known that I, WILLIAM STREETER RICHARDSON, a citizen of the United States, residing at Boston, in the county of Suffolk and State of Massachusetts, have invented a new and useful Improvement in Fastenings for Gloves or other Articles, of which the following is a full, clear, and exact description, reference being had to the accompanying drawings, forming a part of this specification, in explaining its nature.

The invention is a development of the fastening, shown and described in my Letters Patent No. 260,050, the principle of the device being substantially the same as that described in said patent, the improvement consisting in various features of construction and application whereby the fastening is cheapened and when applied has the appearance of a button, which for certain styles of goods is considered to be of some advantage.

Referring to the drawings, Figure 1 represents in plan view a blank from which the cap of the socket member of the fastening is made. Fig. 2 represents in vertical elevation the first form to which the cap portion of the construction is reduced by striking in suitable dies. Fig. 3 is a plan view of the blank from which an intermediate piece or section of the fastening, comprising the ring with yielding sides extending from its inner edge, is formed. Fig. 4 represents in inverted position said intermediate section after it has been submitted to a forming action in suitable dies, whereby the yielding sides have been struck down from the flange or ring. Fig. 5 represents a vertical section of the intermediate section reversed. Fig. 6 is a vertical section of a flanged eyelet such as may be used for securing the cap and intermediate socket-ring to a glove-flap or other article. Fig. 7 illustrates in vertical section the way in which the parts are assembled immediately before a fastening is submitted to the finishing operation, and it comprises the cap, the intermediate ring or flanged socket-piece, and a flanged eyelet, the flange of the eyelet and of the socket-ring being in contact. Fig. 8 is a fastening device in the nature of a collet 50 which is used upon the under surface of the

material to which the fastening is applied. Fig. 9 shows the relation of the collet or turning-washer to the other section of the fastener before they are united. Fig. 10 represents the parts shown secured together, with a ball 55 member H applied thereto.

The socket-fastening is made up of three principal parts—first, the cap; second, the intermediate flange or ring, having the yielding sides or jaws which form the socket, and, 60 third, the fastening device, which is attached to the cap before the fastening is secured in place on the glove-flap or other article. The cap is formed from the disk A by first striking up the disk to the shape shown in Fig. 2, 65 which provides the rounded top *a* and the short sleeve *a'*. B is a disk of spring-brass in which the slit *b* has been formed. The disk thus formed is submitted to a forming operation, whereby the sections are bent downward 70 or away from the flange, so as to form the yielding jaws or sides *c c'* and the ring *c²*, from which the jaws or yielding sides project.

For the fastening part of the device I use an eyelet D having a flange *d*, and it is fastened to the cap with the jaw-ring by drawing the sleeve *a'* of the cap upon the under surface of the eyelet-flange, so that it and the jaw-ring are held between the flange *a²* of the cap and the inner surface of the top thereof. 75 (See Figs. 7 and 8.)

When the eyelet shown in Figs. 6 and 7 is employed, a hole is formed in the material in which the socket member of the fastening is attached, the eyelet passed through the same, 85 and its lower section upset in the collet placed on the under surface of the material. This collet has a central opening, the inclined surface *g* and the flange *g'* overlapping it and forming the space *g²*. The lower edge of the 90 eyelet striking this inclined surface of the collet is turned under the flange *g'*, as represented in Fig. 10. This member of the fastening device when secured in position will have the cap and the ring supporting the jaws 95 or yielding sides of the socket member and one flange of the fastening-eyelet upon one side of the material and the other flange of the fastening-eyelet upon the other side.

This device can be used with any ordinary 100

form of ball-button, or with a stud H, as represented in Fig. 10. This stud is formed from a cap-eyelet, previously provided with the neck h, by first inserting the same through a hole in the material, then slipping a washer upon the same, and then submitting the special washer to pressure, by which it is flattened and its opening contracted about the neck of the stud. This makes a very cheap form of stud and a very efficient method of fastening it in place.

One of the advantages which arise from making the socket member of the fastening in the way herein specified is that the jaws or yielding sides are made of spring-brass, while the remainder of the fastening can be made of soft easily-formed metal. This provides great durability to the principal wearing part of the fastening.

Another advantage is that the fastening, while it retains all the essential features of my said patented invention, can be made more cheaply, and still another advantage arises from the fact that it is more firmly and readily secured in place and in a more compact form.

It will be observed that the cap performs two functions. First, it acts to cover the yielding sides or jaws and prevent dust and dirt from reaching the same, while at the same time it improves the appearance of the fastening, and, second, to keep the socket or jaws securely in place and provide means whereby additional fastening devices may be employed for securing the socket or jaws rigidly in position.

It will be seen that the ball-receiving member of the fastening has its parts assembled together and united before they are secured to the material—that is, the flange of the ball-holder and the flange of the fastening-eyelet are locked or secured to the cap by the folding or lapping of the edge of the cap upon the under surface of the eyelet-flange. This secures the parts together before they are used, making this section of the fastening easy to handle and to apply. It will also be seen

that the fastening as thus made has the cap, the fastening-eyelet extending therefrom secured to the cap, and a ball-holder having a flange also held or secured to the cap and having its ball-holding section extending downward into the barrel of the eyelet, preferably to such an extent as to bring its lower edges very nearly if not quite flush with the under surface of the flange of the eyelet after it has been turned. This manner of holding the jaws and arrangement of the jaws is of importance in that it permits the barrel of the eyelet to hold the ball or head of the fastening in whole or in part and in that it permits the use of a cap either slightly rising from the material to which it is secured or curved, or even flat, the ball-holding space being well within the barrel of the fastening-eyelet; and it will be further observed that this result is obtained without increasing the edge thickness of the fastening to any appreciable extent.

I would say that the form or shape or manner of making the ball-holding section of the fastener is immaterial.

Having thus fully described my invention, I claim and desire to secure by Letters Patent of the United States—

In a fastening for gloves and other articles, the combination of a member comprising a cap, a flanged eyelet, and a ball-holder having a yielding socket-entrance within the barrel of the flanged eyelet, the eyelet and ball-holder being united to the cap by the edge of the cap which is lapped upon their flanges, immediately adjacent thereto and a collet or eyelet-turner having a cone for turning, receiving, holding, and finishing the edge of the eyelet in applying the fastening, and also forming an opening to the said yielding socket-entrance, as and for the purposes described.

WILLIAM STREETER RICHARDSON.
